ULTRASHORT WAVE OSCILLATION
GENERATIONClarence W. Hansell, Port Jefferson, N. Y., as-
signor to Radio Corporation of America, a cor-
poration of Delaware

Application July 28, 1930. Serial No. 471,810

15 Claims. (Cl. 250—36)

This invention has as its main object the provision of new and useful methods and means for the generation of ultrashort wave length electrical oscillations.

5 In order to produce ultrashort electromagnetic wave energy, it is a further object of this invention to provide for the production of a discharge through a colloidal solution whereby, upon the starting and cessation of the discharge, the 10 particles in solution will vibrate electrically at a frequency corresponding to their natural wave length. As the particles in solution are very small, the frequency will be correspondingly high, and they will be of the order of magnitude, in 15 wave length, of a small fraction of a centimeter.

Waves of this order of magnitude may be treated like light waves, in that they may be efficiently transmitted by the provision of a suitable reflector.

20 In order to cause increased efficiency of oscillation throughout the colloidal solution, it is a further object of my invention to provide for uniform current distribution throughout the solution and this I do by causing the discharge 25 to take place throughout the whole volume of the solution. Moreover, for this purpose, I increase the pressure of the solution and, cause discharge preferably by virtue of a radio frequency potential applied to the solution superimposed upon a 30 unidirectional biasing potential, or combined with a low frequency alternating potential.

In the accompanying drawing which is only illustrative of the principles of my invention and not in any way limitative thereof,

35 Figures 1 and 2 are plan and elevational views of a form of ultrashort wave length oscillator utilizing, for the production of oscillations, a discharge through a colloidal solution within a container, and,

40 Figures 3 and 4 are similar views of a modification wherein discharge through a colloidal solution is caused to propagate itself through a series of colloidal particles over a long path; or, in other words, through a large volume of the solution.

45 It has been found that when a spark discharge takes place through a colloidal solution containing metallic particles the discharge grape vines itself through the liquid from one solid particle to another so that there are a whole series of 50 sparks off the ends of the particles. These sparks set up damped electrical oscillations in each particle at a wave length corresponding to the natural period of electrical oscillations of the particle in the liquid. If the particles are of 55 substantially uniform shape and size their natural

periods will be substantially equal and the radiation from a volume of solution will be confined to a rather narrow wave length band. In order to make the discharge take place more or less uniformly throughout the volume of a quantity 60 of solution the liquid may be subjected to heavy pressure. This pressure not only helps to distribute the current, but also causes better quenching of the sparks and consequently higher efficiency.

In order to further increase the dispersion of 65 current through the solution and to permit a maximum amount of power dispersion per unit of volume, radio frequency currents may be employed either alone or in combination with low frequency or direct current to produce the sparks. 70 In such case the relatively high radio frequency currents employed create reactance in the solution which aids in giving a uniform current distribution. It is to be understood, of course, that the electrodes employed would also be designed 75 to give a uniform potential distribution in the volume of the solution which is desired to be active.

Referring to Figures 1 and 2, within a glass or 80 quartz cylinder 2 terminated by metallic stoppers or electrodes 4, 6, there is placed under pressure a liquid containing finely divided metal particles forming a colloidal solution. The particles suspended therein are, preferably, of uniform size. By applying, from a suitable source 8, modulated or chopped high voltage unidirectional potentials, or radio frequency potentials superimposed upon a direct current potential or radio frequency potentials combined with a low frequency alternating current potential, a discharge 85 will occur in the colloidal solution in container 2. By suitable choice of maximum values for the undulating potentials applied and by virtue of the short time during which the potential is high together with the effect of the corona on each 90 particle increasing the break down potential for the whole volume of liquid, the conditions for production of ultrashort wave oscillations may be obtained without a complete disruptive or short circuiting discharge through the liquid. In 100 other words the potential is made to pass through the corona point, for the particles in the solution, at a rapid rate. Upon the starting and cessation of the discharge, the particles in solution will vibrate electrically at their own natural period 105 and produce electromagnetic waves. As these waves are very short in wave length, they may be efficiently reflected by a suitable reflector 10.

The reflector is preferably made parabolic and should be placed about the container 2 as shown, 110

for the reason that radiation from the container is least directive in a plane perpendicular to its longitudinal axis. If desired, the reflector and container may be immersed in a liquid identical with the main body of the liquid of the solution.

The colloidal solution need not be placed within a cylindrical container, but may be placed within a container of parabolic form of either glass or quartz as shown in Figures 3 and 4 under suitable pressure by means of a suitable valve 12. The parabolic surface of the container 14 of Figures 3 and 4 is preferably silvered or sputtered with a metal coating so as to cause efficient reflection of the oscillations.

15 In order to provide for the elongation and continuous change of path of the discharge between electrodes 16, 18 suitably supported within the solution, an electrical field may be applied to the discharge in a direction traversing its general 20 longitudinal axis, by means of electrodes 20, 22 to which suitable potentials may be applied, either direct or alternating through leads 24.

A disruptive or short circuiting discharge may also be used to produce ultrashort waves by 25 placing electrodes 20, 22 by electromagnets, the magnetic field produced thereby being passed through the solution and being sufficient to cause the discharge to wobble or grapevine itself through the solution so that it engages a continuously changing set of particles. With a magnetic field, the grapevining effect is increased if iron or any other magnetic substance is used for the particles in the colloidal solution.

Having thus described my invention, what I 35 claim is:

1. In high frequency apparatus comprising a colloidal solution containing metallic particles the method of generating ultrashort electromagnetic waves which includes producing a non-disruptive discharge in said colloidal solution by applying an undulating potential thereto whose maximum is sufficient to cause only the non-disruptive discharge.

2. The method of generating ultrashort electromagnetic waves which includes producing a discharge through a colloidal solution, and applying a field in a direction traversing the direction of the discharge in order to cause continuous change in the path of the discharge through 50 the solution.

3. The method of generating ultrashort electromagnetic waves which includes applying an undulating potential to a colloidal solution whose maximum value is sufficient to cause a discharge 55 through the solution, and applying a field in a direction traversing the direction of the discharge in order to cause elongation of the path of the discharge through the solution.

4. The method of producing a beam of ultrashort electromagnetic wave energy which includes producing a discharge through a colloidal solution by means of an undulating potential whose maximum value is sufficient to cause the discharge, applying a field in a direction traversing 60 the direction of the discharge to cause change in path thereof through the solution, and reflecting the oscillations set up by the particles in solution.

5. In high frequency apparatus comprising a 70 colloidal solution containing metallic particles the method of producing ultrashort electromagnetic waves which includes producing a discharge

through said colloidal solution, and stopping the discharge so that the metallic particles in solution oscillate freely at a period corresponding to their natural period.

6. High frequency oscillatory apparatus comprising the combination of a colloidal solution having metallic particles therein and means for producing a discharge in the solution. 80

7. High frequency oscillatory apparatus comprising the combination of a colloidal solution having metallic particles therein, means to produce a discharge in the solution, and means for applying a pressure to the solution. 85

8. High frequency oscillatory apparatus comprising the combination of a colloidal solution, 90 means for causing a discharge in the solution, and means for causing elongation of path of the discharge through the solution.

9. High frequency oscillatory apparatus comprising the combination of a colloidal solution, 95 means for causing a discharge through the solution, means for applying a pressure to the solution, and means for applying a field to the discharge in a direction traversing the direction of the discharge in order to cause grape-vining 100 thereof through the solution.

10. High frequency oscillatory apparatus comprising the combination of a colloidal solution, means for causing a discharge through the solution, means for applying a pressure to the solution, means for applying a field to the discharge in a direction traversing the direction of the discharge in order to cause grapevining thereof, and a reflector for reflecting electromagnetic waves set up by variations of the particles in solution. 110

11. High frequency apparatus comprising the combination of a container having a colloidal solution therein, said container being immersed in a body of liquid identical with the main body of liquid in the colloidal solution, and means for 115 producing a discharge through the colloidal solution.

12. The method of generating ultrashort electromagnetic waves which includes producing a disruptive discharge through a colloidal solution, 120 and applying a field in a direction traversing the direction of the discharge in order to cause continuous change in the path of the discharge through the solution.

13. The method of generating ultrashort electromagnetic waves which includes applying an undulating potential to a colloidal solution whose maximum value is sufficient to cause a disruptive discharge through the solution, and applying a field in a direction traversing the direction 130 of the discharge in order to cause elongation of the path of the discharge through the solution.

14. The method of producing a beam of ultrashort electromagnetic wave energy which includes producing a disruptive discharge through a colloidal solution by means of an undulating potential whose maximum value is sufficient to cause the discharge, applying a field in a direction traversing the direction of the disruptive discharge to cause change in path thereof through 140 the solution, and reflecting the oscillations set up by the particles in solution.

15. Transmitting apparatus having, in combination, a colloidal solution containing metallic particles, and means for producing a discharge 145 through said solution.

CLARENCE W. HANSELL.
